UNITED STATES PATENT OFFICE.

CHRISTOPH A. GIEBELE-R-WANKE, OF NEW YORK, N. Y.

JOINTED DOLL.

1,348,216.

Specification of Letters Patent.

Patented Aug. 3, 1920.

Application filed July 26, 1918. Serial No. 246,817.

To all whom it may concern:

Be it known that I, CHRISTOPH ADOLPH GIEBELE-R-WANKE, a citizen of Germany, and a resident of the borough of Manhattan, in the county, city, and State of New York, have invented certain new and useful Improvements in Jointed Dolls, of which the following is a specification.

The present invention relates to improvements in jointed dolls, and has for an object to provide a doll which will be life-like in appearance and in the positions it may assume will be practically unbreakable, and will lend itself to economic and simple manufacturing methods, to the end that such dolls may be manufactured in large quantities and comparatively cheaply. More particularly, an object is to provide a doll, the body and limbs of which may be constructed of wood or other analogous material capable of being turned or otherwise formed to shape by automatic machinery. It is also proposed to provide an improved knee and hip joint construction which will enable the doll to assume proper kneeling and sitting positions, and also it is proposed to provide a shoulder, elbow and wrist joint construction permitting a latitude of movements to the upper and lower arm sections and the hand heretofore impossible in dolls, such movement simulating the corresponding movements of these members of the human body.

With these and other objects in view, an embodiment of my invention is shown in the accompanying drawings, and this embodiment will be hereinafter more fully described with reference thereto, and the invention will be finally pointed out in the claims.

In the accompanying drawings:

Figure 1 is a view partly in elevation, and partly in vertical section of a doll embodying my improvements.

Fig. 2 is a side view partly in section.

Fig. 3 is a vertical sectional view of the arm.

Fig. 4 shows the leg in kneeling position, and

Figs. 5 and 6 are detailed sectional views of the wrist joint.

Similar reference characters indicate corresponding parts throughout the several figures of the drawings.

Referring to the drawings, and more particularly Fig. 1 thereof, the body portion

10 which is formed preferably of wood, is provided with a central bore or passage of relatively large diameter, extending from the neck recess or socket 12 to a point substantially below the center of the body. The leg sockets 13 and 14 are provided at the lower end of the body and passages 15 and 16 are bored upwardly from these sockets to a point substantially above the 65 end of the bore 11, these passages being separated by a central portion 17 and communicating with the said bore 11.

The body is shaped off as at 18 forming inclined surfaces intersecting the leg sockets 70 and extending from a point above the said sockets to the transverse medial line thereof.

Arm holes 19 and 19^a are bored at each side of the upper end of the body and communicate with the central passage 11. 75

The arms comprise a tubular upper arm section 20 preferably formed of wood and turned to shape, the said section being provided at its upper end with an enlarged ball shaped portion 21, the circular line of intersection between the ball shaped portion 21 and the main portion of the section 20 being slightly below the arm hole of the body, in the assembled position of the doll as shown in Fig. 1. A transverse vertically 85 disposed slot 22 is provided in the ball shaped portion 21, said slot communicating with the bore 23 of the section 20, through a reduced passage 21^a and having its base disposed below the transverse axis of the 90 said ball shaped portion and above the circular line of intersection between the said portion 21 and the portion 20.

At the lower end of the section 20, there is provided a spherical socket 24 in communication with the bore 23, and an inclined surface 25 is produced at the lower end of the section 20, extending preferably from the transverse medial line of the lower end of the section 20 to a point above the base of 100 the socket. The plane of the surface 25 is disposed transversely to the plane of the slot 22.

The lower or fore-arm section 26 is also preferably turned to shape and is provided 105 with a central bore or passage 27. Sockets 28 and 29 are provided at the respective ends of the section 26, and these are intersected by inclined surfaces 30 and 31. A spherical and symmetrically shaped ball 110 joint member 32 is rigidly secured by gluing or the like, in the socket 28 at the upper

end of the section 26 and is provided with an axial bore 33 and a radial longitudinal slot 34 (Fig. 3) cut from the outer surface of the said member to said bore, this slot being 5 disposed centrally of the inclined surface 25. In the socket 29, there is rotatably mounted a spherically shaped joint member 35 having a transverse slot 36 cut there-in and extending slightly more than half-way therethrough. A pin 37 extends through the said member transversely to the slot. A hook 38 is pivotally secured at one end to the pin and at the other end there is secured an elastic cord 39 which extends 10 through the bore 27 of the section 26, the bore 23 of the section 20, the slot 22, the arm holes 19 and 19^a, and similarly down through the other arm, and is secured at its other end to a similar hook provided on the 15 other wrist joint member. The ball joint member 35 may be turned to any position of rotation within the socket 29, while the slot 36 permits the same to be pivotally moved about the pin 37 and by co-operation 20 with the inclined surface 31 the hand may be moved to a position substantially at right angles to the axis of the lower arm section. A dove tail shaped extension 40 is formed upon the ball joint member 35, during the 25 turning of the same, the hand 41 being molded upon the said member and being securely held in place by the said extension.

With my improved shoulder-joint, the arm may be raised to practically any position and may be carried above the head either by swinging in the direction of the arrow indicated in Fig. 1, or by rotating the same in the direction of the arrow indicated in Fig. 2. The elbow joint permits of the lower or forearm section being swung with respect to the upper-arm section to a position such as indicated in Fig. 3, similar to the position that may be assumed by the 30 human arm.

The legs comprise an upper limb or thigh section 42 preferably formed of wood and turned to shape, provided with a cylindrical bore 43 extending therethrough. A large socket 44 is provided at the upper end and 35 a relatively small socket 45 is provided at the lower end, these sockets being in communication with the cylindrical bore. An inclined flat surface 46 is produced at the upper end of the section 42 by removing a portion thereof, and at the lower end another inclined surface 47 is produced in a similar manner, and at the other side of the section. A spheroidal shaped joint member 48 also formed of wood and turned 40 to shape is provided with an axial bore 49, and a radial longitudinal slot 50 is cut from the outer surface of the said member to the said bore. The member 48 is rigidly secured in the socket 44, its axis being substantially 45 coincident to the axis of the member 42, the

slot 50 being disposed centrally of the inclined surface 46.

The lower limb section 51 is provided with a cylindrical bore 52 extending therethrough, and at its upper end is provided 70 with a spherical socket 53 in communication with the bore 52. An inclined surface 54 is provided at the upper end of the section 51 intersecting the socket 53, and opposed in position to the inclined surface 47 of 75 the section 42. A spherical shaped ball joint member 55 is rigidly secured in the socket 53 of the member 51, being provided with a bore 56 extending therethrough and in 80 communication with the bores 43 and 52 of the sections 42 and 51 respectively, and with a radial longitudinal slot 57 extending from the outer surface to the bore, and disposed substantially centrally of the inclined surface 85 54.

The lower end of the section 51 is recessed as at 58, and a foot section 59 also preferably formed of wood is disposed therein. The foot section is turned to shape two 90 feet being formed from one piece simultaneously, which is then split to form the separate feet, the upper portion of the feet engaged by the recess, being cylindrical so that the foot is yieldably held against turning movement. The foot section is provided with a hook 60 to which is secured the lower end of an elastic cord 61, said cord extending upwardly through the bores 52, 56, 43 and 49, and being provided at its upper 95 end with a hook 62 which is engaged with a transverse rod 63 disposed in the body 10 and extending across the upper portion of the passages 15 and 16. Both legs are independently secured in a similar manner 100 to this rod, and the head 64 is also secured thereto within the socket 12, by means of the elastic cord 65 and the hook connections 66 and 67. The independent stringing of the head, the two legs and the arms greatly 105 facilitates the assembling of the doll, improves the functioning of the various joints, and enables any of the various parts of the same to be readily removed without disturbing the other parts. 110

The elbow joints, the hip joints and the knee joints, it will be noted, are substantially similar in construction and operation, permitting of both a turning movement of the limbs and a swinging movement. In the 115 sitting or kneeling position of the doll and in the moved position of the forearm in Fig. 3, the elastic cord exerts both a rearward and upward pull, the resultant force of which firmly holds the inclined surfaces 120 to each other, the cord being substantially at right angles to the inclined surfaces, and extending at each side and adjacent thereto, so that there will be no danger of the 125 doll wabbling. This action is possible be- 130

cause of the novel arrangement of the slots, these slots extending to the inclined surfaces. In the straightened out position of the members, there is a direct vertical pull upon the 5 elastic cord which holds the members firmly in their straight positions.

I have illustrated and described a preferred and satisfactory embodiment of my 10 invention, but it is obvious that changes may be made therein within the spirit and scope thereof, as defined in the appended claims.

I claim:

1. In a doll, the combination with a body portion having limb engagement sockets, of 15 limb members, each comprising a pair of tubular members adapted to be swung relatively to each other, said members being provided at their adjacent ends with co-operating balls and sockets, and opposed inclined 20 surfaces intersecting the surfaces of said balls and said sockets, the center of the inner edges of said inclined surfaces being substantially central of the longitudinal length of said inclined surfaces, said balls being 25 each provided with a longitudinal bore and a radial slot extending from said bore to the surface of said member and unobstructed throughout the longitudinal length of said member, said slot extending 30 unobstructed from said centers of the inner edges of said inclined surfaces, said limb members being provided at one end with a ball joint member engaging the sockets of 35 said body portion, an extremity member at the other end of said limb members, and connection means extending from said extremity member through said tubular members to a point of attachment within said 40 body portion, a portion of said connection means adapted to be disposed substantially 45 at right angles to said inclined surfaces in the engagement position thereof, and adjacent the centers of the inner edges thereof to exert a positive force to hold said surfaces in engagement with each other.

2. In a doll, the combination with a body portion having limb engagement sockets, of an arm member comprising a pair of tubular members adapted to be swung relatively to 50 each other, one of said members being provided with a ball shaped portion having a transverse vertical slot therein, said ball shaped portion rotatably and pivotally engaging one of said limb engagement sockets, 55 said tubular members being provided at their adjacent ends with balls and sockets and opposed inclined surfaces, said balls being provided with radial slots extending unobstructed between said inclined surfaces, a 60 hand member at the end of the other said tubular member, and connection means extending from said hand member through said tubular members to a point of attachment within said body portion, a portion of 65 said connection means adapted to be dis-

posed substantially at right angles to said inclined surfaces in the engagement position thereof, to exert a positive force to hold said surfaces in engagement with each other.

3. In a doll, the combination with a body portion having arm engagement sockets disposed transversely to the vertical axis of 70 said body, of arm members comprising a pair of tubular members adapted to be swung relatively to each other, one of said 75 members being provided at its upper end with an enlarged ball shaped portion engaging said limb engagement socket, and of greater diameter than said limb engagement socket, said ball shaped portion being provided with a transverse slot therein, having its base parallel to and slightly below the axis of said arm engagement socket in the lowered position of said arm, a hand member at the end of the other said member and 80 connection means extending from said hand member through said tubular members, said slot of said ball shaped portion and said arm engagement socket to a point of attachment within said body portion, said arm 85 adapted to have rotating and swinging movement in said socket.

4. In a doll, the combination with a body portion provided with leg engagement sockets and inclined surfaces intersecting 95 said sockets, of leg members comprising tubular members adapted to be swung relatively to each other, one of said members being provided at its upper end with a socket and an inclined surface intersecting 100 said socket and opposed to said inclined surface of said body portion, a ball joint member secured in said socket and rotatably engaging the said socket of said body portion, said ball joint member being provided 105 with a longitudinal bore and a longitudinal radial slot extending unobstructed between said inclined surfaces, connection means extending through said tubular members to a point of attachment within said body portion, a portion of said connection means 110 adapted to be disposed substantially at right angles to said inclined surfaces in the engagement position thereof, to exert a positive force to hold said surfaces in engagement 115 with each other.

5. In a doll, a wrist joint construction comprising a tubular forearm section provided at its lower end with an inclined surface and a socket, said inclined surface extending from the center of said socket to one side of said section and intersecting said socket, and a hand member provided with a ball shaped portion engaging said socket, said ball shaped portion having a transverse 120 slot therein, and a pintle extending transversely of said slot, and connection means extending through said tubular forearm section and pivotally engaging said pintle, said hand member adapted to have rotating 125 130

and swinging movement with relation to said forearm section and adapted by engagement with said inclined surface to assume a substantially right angular position to said forearm section.

6. In a doll, a leg construction comprising a pair of tubular members adapted to have swinging movement with relation to each other, one of said members being provided at its lower end with a cylindrical recessed portion, a foot member having an upper cylindrical portion engaging said recessed portion, and elastic connection means extending from said foot member through said tubular member, engagement of said cylindrical portion of said foot with said cylindrical recessed portion adapted to hold said foot during full engagement of said foot with said recessed portion against lateral turning movement relatively to said tubular member.

7. In a doll, the combination with a body portion having a longitudinal bore therethrough and leg engagement sockets in com-

munication therewith, of leg members each 25 comprising a pair of tubular members adapted to be swung relatively to each other and provided at their ends with foot members, connection means extending from said foot members through said tubular members and said sockets, and a transverse bar extending across said sockets and said longitudinal bore of said body, said connection means being secured to said bar, a head member engaging the upper end of said bore, and connection means extending from said head member through said bore and connected to said transverse bar.

8. In a doll, a hand construction comprising a ball joint member turned to shape, 40 and having a dovetailed extension thereon, and a hand portion molded on said ball portion and held thereon by said dove-tail shaped extension.

In testimony that I claim the foregoing 45 as my invention I have signed my name.

CHRISTOPH A. GIEBELER-WANKE.
